COMBINATION CABINET HAVING A FIRE- PLACE AND DINETTE SET THEREIN

Murray Golod and David Kantrowitz, New York,
N. Y.; said Golod assignor to Bernard D. Co-
len, New York County, N. Y.

Application October 9, 1935, Serial No. 44,152

6 Claims. (Cl. 155—124)

This invention relates to new and useful improvements in a combination cabinet having a fireplace and dinette set therein.

The modern trend towards conserving space 5 is well exemplified by this decorative fireplace which may also serve as a dinette when desired.

An object of the invention is the provision of a hollow fireplace having a fire bed in the center of the bottom thereof and panels at the sides and 10 at the top of the fireplace behind which the parts of the dinette are normally housed and may be extended as needed.

Still further the invention contemplates an arrangement wherein the fireplace has a top 15 center panel which may be opened to expose a table extendible and adapted to be used in conjunction with benches extendible from the side panels.

Still further the invention proposes a novel arrangement for constructing the extendible table 20 of sections, and a provision for automatically latching these sections against accidental folding.

Another object of the invention is the construction of a device as mentioned which is simple and durable and which may be manufactured and 25 sold at a reasonable cost.

For further comprehension of the invention, and of the objects and advantages thereof, reference will be had to the following description 30 and accompanying drawings, and to the appended claims in which the various novel features of the invention are more particularly set forth.

In the accompany drawings forming a material part of this disclosure:—

Fig. 1 is a front elevational view of a combination dinette and fireplace constructed according 35 to this invention.

Fig. 2 is a perspective view of Fig. 1 but illustrating the dinette in operative position.

Fig. 3 is a sectional view taken on the line 3—3 of Fig. 1 with a schematic showing of the table 40 extended.

Fig. 4 is a sectional view taken on the line 4—4 of Fig. 1 with a schematic view showing one of 45 the benches extended.

Fig. 5 is a fragmentary horizontal sectional view taken on the line 5—5 of Fig. 1.

Fig. 6 is a fragmentary sectional view taken on the line 6—6 of Fig. 2.

Fig. 7 is a sectional view taken on the line 7—7 of Fig. 1.

Fig. 8 is a sectional view taken on the line 8—8 of Fig. 6.

Fig. 9 is an enlarged detail view of a portion of 55 Fig. 6.

Fig. 10 is a sectional view taken on the line 10—10 of Fig. 9.

The combination dinette and fireplace, according 5 to this invention, comprises a hollow fireplace 10 having a fire bed 11 in the center and at the bottom thereof, a top central panel 12 above said fire bed and side panels 13 at the sides thereof. An extendible table 14 is mounted in the space behind the top central panel 12. Extendible benches 13' are mounted in the space 10 behind said side panels 13.

The benches 13' consist of said panel portions 13, the same side panels before referred to, and supporting legs 15 and 16. The legs 15 are mounted at the outer ends and about the middle of the panels 13 and are normally held at right angles thereto by supporting arms 17, such as is usually used to hold similar parts. The legs 16 are equipped with support elements 18 such as rollers, which engage tracks 19 from the 20 sides of compartments arranged behind said side panels. These tracks (see Fig. 4) extend in a curve from the bottoms to the tops of the compartments.

The compartments are formed by transverse 25 partitions 21 and 22 dividing the interior of the fireplace. The tracks 19 are mounted respectively upon the sides of these partitions and the inner face of the side walls of the fireplace.

The panel 12 is supported by several hinges 30 35 23 at its bottom edge so as to be pivotable to an opened position as clearly shown in Fig. 2. When opened, it is possible to extend the table. The table consists of a rear table top section 14^a hingedly connected with a front table top section 14^b. A supporting leg 25 is hingedly mounted to the outer end of the table top and is held at right angles thereto by pivoted arms 26. The details of these arms will not be given as they are generally known in the furniture art. Within 40 the side compartments there are shelves 27 which may be used to store objects.

An automatic means is provided for latching the sections 14^a and 14^b of the table top into extended positions automatically when the table is opened. This means consists of a bolt 30 fixedly mounted on a stem 31 which is slidably mounted through a washer 30' which is fixedly mounted in the section 14^a. The bolt 30 is slidably mounted in the section 14^a, and in extended 45 position is adapted to engage in a keeper opening 34 in the edge of the front table section 14^b. A coaxial spring 32 is mounted on the stem 31 and acts between the bolt 30 and the washer 30' to 50 55

urge the bolt 30 forward to engage in the keeper 34.

A pin 35 projects from the stem 31 and engages a slot 36 in the rack 33. The rear end of the 5 rack 33 meshes with a pinion 37 rotatively supported on the table top section 14^a. This pinion is much wider than the width of the rack so as to have an extending portion. This extending portion meshes with a rack 38 mounted in the 10 section, 14^a at right angles to the rack 33. The rack 38 is urged laterally by a spring 39 coaxially thereon acting against a collar 40 on the rack and a portion of the table top 14^a.

The pin 35 engages the slot 36 to allow the 15 bolt 30 to be withdrawn from the keeper 34 by the rearward movement of the rack 33.

A support element or roller 41 is mounted upon the extended end of the rack 38. This roller 41 engages in a vertical track element 42 mounted 20 upon the partition 21. The other side of the table section 14^a is provided with a supporting element or roller 41' engaging in a vertical track 42' mounted upon the partition 22. These tracks 42 and 42' extend downwards behind the fire 25 bed 11, as clearly shown in Fig. 3 and also horizontally at 42^b for holding the table when in open position. The arrangement is such that the table top may be moved into the compartment behind the fire bed. One of tracks 42 has 30 an enlarged portion 42^a (see Fig. 8) at its top end so that the spring 39 may move the rack 38 when the table top is in the extended position.

The operation of the device is as follows:—
35 Fig. 2 shows the extended position of the dinette. In this position the fireplace may be used as a dinette. When it is desired to fold the dinette, it is merely necessary to lift up the inner ends of the bench seats 13' to a position 40 in which the bench seats are vertical and disposed into the open sides of the side walls of the fireplace and form the panels 13. Fig. 4 shows the bench seats in the closed position, the seat portions thereof then constituting the side 45 panels 13. The side arms 16 straddle the shelf 27 as clearly shown in Fig. 5.

Friction is depended upon to maintain the side panels in their positions. The dot and dash lines in Fig. 4 indicate the extended positions of 50 the benches.

The table may be collapsed by first pulling it out on the horizontal tracks and then lifting the outer end slightly so that the inner end may move slightly down along the tracks 42 and 42'. 55 This causes the roller 41 to be moved inwards against the action of the spring 39. Thus, the rack 38 moves inwards and turns the pinion 37 which retracts the bolt 33. The front table top section may now be moved about its hinges over 60 the rear section 14^a. The dot and dash lines in Fig. 3 clearly show the folded position. The leg 25 may be folded flat against the underside of the section 14^b, which when moved on the section 14^a is on the top side. The table may then 65 be moved into the compartment of the fireplace to a position shown by the full lines in Fig. 3. It is held in position by an adjustable hook 40 swivelly mounted upon the back wall of the fireplace.

70 When the table is extended from the closed position, shown in Fig. 3, to the open position, the bolt 30 will be extended to engage the keeper 34 automatically, the bolt being released from 75 its retracted position. It will be withdrawn from

this latter position when the roller 41 engages the narrow portion of the track 42.

It is to be understood that the shape, design and proportions of the fireplace and the dinette may be changed as desired. Also that any number and type of supporting legs may be used for benches 13'. Instead of using one bolt 30, two or more may be provided.

While we have illustrated and described the preferred embodiment of our invention, it is to 10 be understood that we do not limit ourselves to the precise construction herein disclosed and the right is reserved to all changes and modifications coming within the scope of the invention as defined in the appended claims. 15

Having thus described our invention, what we claim as new, and desire to secure by United States Letters Patent is:—

1. In a combination cabinet having a fireplace and dinette set therein, comprising a compartmented body having an opening for a fire bed in the center at the bottom thereof, a top central movable panel above said opening, and side movable panels at the sides of said opening, an extendible table mounted in the compartment behind said top central panel and said opening and said side panels being extendible to form benches, said extendible table being constructed of sections, consisting of an inner section hingedly connected with an outer section, the outer section having a hingedly mounted foot adapted to be held at right angles thereto, the inner section having supporting elements engaging tracks mounted within said cabinet, and means for holding said sections of the table from closing 35 when the said table is in the open position, comprising a bolt slidably mounted on the inner section and engageable with a keeper on the outer section, a rack slidably mounted in the inner section and connected with said bolt and engaging a pinion mounted on said inner section, a transverse spring pressed sliding rack on the inner section engaging said pinion and provided with a support at one side of the rear table top section and engaging a track in said cabinet, 40 another support on the other side of the rear table top section engaging another supporting track in said cabinet, and a portion of the first mentioned track being enlarged at one portion at which the support member engages to permit 45 said bolt to engage said keeper when the table top is extended.

2. In a combination cabinet having a fireplace and dinette set therein, comprising a compartmented body having an opening for a fire bed in 55 the center at the bottom thereof, a top central movable panel above said opening, and side movable panels at the sides of said opening, an extendible table mounted in the compartment behind said top central panel and said opening and said side panels being extendible to form benches mounted in the space behind said side panels, said extendible table being constructed of sections, consisting of an inner section hingedly connected with an outer section, the outer section having a 60 hingedly mounted foot adapted to be held at right angles thereto, the inner section having supporting elements engaging tracks mounted within said cabinet, and means for holding said sections of the table from closing when the said table is in the open position, comprising a bolt slidably mounted on the inner section and engageable with a keeper on the outer section, a rack 65 slidably mounted in the inner section and connected with said bolt and engaging a pinion 70

75

- mounted on said inner section, a transverse spring 5
pressed sliding rack on the inner section engaging
said pinion and provided with a support at one
side of the rear table top section and engaging a
track in said cabinet, another support on the
other side of the rear table top section engaging
another supporting track in said cabinet, and a
portion of the first mentioned track being en- 10
larged at one portion at which the support mem-
ber engages to permit said bolt to engage said
keeper when the table top is extended, said en-
larged portion being horizontal.
3. In a combination cabinet having a fireplace
and dinette set therein, comprising a compart- 15
mented body having an opening for a fire bed in
the center at the bottom thereof, a top central
movable panel above said opening, and side move-
able panels at the sides of said opening, an extend-
ible table mounted in the compartment behind 20
said top central panel and said opening and said
side panels being extendible to form benches, said
extendible table being constructed of sections,
consisting of an inner section hingedly connected
with an outer section, the outer section having a 25
hingedly mounted foot adapted to be held at
right angles thereto, the inner section having
supporting elements engaging tracks mounted
within said cabinet, and means for holding said
sections of the table from closing when the said 30
table is in the open position, comprising a bolt
slidably mounted on the inner section and en-
gageable with a keeper on the outer section, a
rack slidably mounted in the inner section and
connected with said bolt and engaging a pinion 35
mounted on said inner section, a transverse
spring-pressed sliding rack on the inner section
engaging said pinion and provided with a sup-
port at one side of the rear table top section and
engaging a track in said cabinet, another sup- 40
port on the other side of the rear table top section
engaging another supporting track in said cabi-
net, and a portion of the first mentioned track be-
ing enlarged at one portion at which the support
member engages to permit said bolt to engage 45
said keeper when the table top is extended, and
a corresponding horizontal track being provided
to permit the sliding of the inner end of table
to the interior of the fireplace.
4. In combination, a cabinet table and benches, 50
a simulated fireplace in the bottom at the center
of the cabinet, a movably mounted top central
panel above said fire place, and side compart-
ments at the sides of said fire place, and extendible
table mounted in the space behind said top cen- 55
tral panel and extendible benches mounted in
said side compartments, said extendible table
being constructed of sections, consisting of an
inner section hingedly connected with an outer
section, the outer section having a hingedly 60
mounted foot adapted to be held at right angles
thereto, the inner section having supporting ele-
ments engaging tracks mounted within the cabinet
behind said fire place, and means for holding said
sections of the table from closing, comprising a 65
bolt slidably mounted on the inner section and
engageable with a keeper on the outer section, a
longitudinally slidable rack on the inner section
connected with said bolt and engaging a pinion
mounted on said inner section, a spring-pressed 70
rack laterally slidable on the inner section and
engaging said pinion and provided with a sup-
porting element at one side of the inner table top
section and engaging a track, another supporting
element on the other side of the inner table top
section engaging another supporting track, and a
portion of the first mentioned track being en-
larged at one portion at which the supporting
element engages when the table top is extended,
and a corresponding horizontal track being pro-
vided to permit the sliding of the inner end of
table to the interior of the fireplace.
